UNITED STATES PATENT OFFICE.

EDWARD POSSON, OF CHICAGO, ILLINOIS.

CAR-FRAME.

940,357.

Specification of Letters Patent. Patented Nov. 16, 1909.

Application filed October 21, 1907. Serial No. 398,462.

To all whom it may concern:

Be it known that I, EDWARD POSSON, a citizen of the United States, residing at Chicago, in the county of Cook and State of Illinois, have invented certain new and useful Improvements in Car-Frames, of which the following is a specification.

One of the objects of my invention is to provide an improved end sill for cars.

Another object is to combine an end sill and center sill in an improved way.

These and other objects will be made apparent in the following specification and claims.

Referring to the drawings—Figure 1 is an elevation of the end sill. Fig. 2 is a section of one end thereof looking in the same direction as in Fig. 1. Fig. 3 is a top plan view of one end of the end sill. Fig. 4 is a section on the line 4 in Fig. 3, looking in the direction of the arrow. Figs. 5, 6 and 7 are sections taken respectively on the lines 5, 6 and 7 in Fig. 1, looking in the directions of the arrows.

The end sill comprises a vertical rear plate 15, a vertical front plate 16 and a substantially horizontal connecting web 17. Corresponding to this web 17 there is a rib 18 running along the front side of the plate 16. At each end of the end sill, that is at each corner of the car, there is a socket 19 adapted to receive the end of the side sill 20.

The front and rear plates 16 and 15 are connected by tubes 21, 22 and 23 which lie in the web 17. These tubes are adapted to receive the ends of the truss rods of the car. At the center part of the end sill the rib 18 projects forward, as indicated by the reference numeral 18^a, and on its edge the vertical plate 25 stands supported from the front plate 16 by the bracing web 26. This front plate 16 is widened at the center, as indicated by the reference characters 16^a and 16^b. The whole end sill has a notch 26^a at the middle of the lower side to receive the draw-bar. On each side of this notch the horizontal plates 27 extend out from the bottom edge of the front plate 16. The horizontal plate 27 is supported at each end thereof by the webs 28 and 29, which project out from the front plate 16. The parts described thus far belong to the end sill and are integral therewith.

Two channel beams 30 are placed near together with their webs vertical and with their flanges turned away from each other.

These two channel beams taken together constitute the center sill of the car. The flanges of each channel beam embrace a wooden member 31. A hole 32 conforming in shape to the cross section of the channel beam 30, as shown in Fig. 2, is cut through the rear plate 15. To unite the center sill members to the end sill, the end of each channel beam 30 is thrust through the hole 32 in the rear plate 15 until it abuts the front plate 16. A cross web 37 extends between the front and rear plates 16 and 15 alongside the hole 32 and the end of the channel beam 30 is riveted to this cross web 37 by means of the rivets 70. From the lower edge of the part 15^b of the rear plate 15 a horizontal tongue 33 projects back under the wooden member 31, and is attached thereto by the vertical bolts 34. This wooden member 31 abuts the rear plate 15. A strengthening web 36 extends diagonally across between the rear plate 15 and the cross web 37.

This end sill is so designed as to have great strength in proportion to its weight; it is integral in construction so that it cannot easily get out of order; and the connection with the center sill members is very secure. The ends of the channel beams 30 do not have to be modified or shaped in order to connect them to the end sill and no extra brackets or other members have to be used for this purpose.

I claim:

1. In a car, the combination of an end sill comprising front and rear plates with a connecting web, and a longitudinal center sill comprising a channel beam, the rear plate of the end sill having a hole corresponding in shape to the section of the channel beam. 90

2. In a car, the combination of an end sill comprising front and rear vertical plates and a vertical cross web near the center thereof, and a longitudinal sill comprising a channel beam, the rear plate of the end sill 100 having a slot beside the said cross web adapted to receive the end of the said channel beam.

3. In combination an end sill consisting of front and rear plates, the rear plate having a slot therein, and a center sill comprising a channel beam with its flanges embracing a wooden beam, the end of the channel beam projecting through the said slot and abutting the front plate and the 111 end of the wooden beam abutting the rear plate.

4. In a car, an end sill comprising front and rear plates connected by a horizontal web, tubular enlargements in said web adapted to receive the ends of the car truss rods, and a seat between the front and rear plates adapted to receive the end of the center sill.
5. In a car, the combination of an end sill comprising a vertical plate with a slot there-
10 in and a rearwardly projecting tongue, and a center sill member consisting of a wooden beam embraced by the flanges of a channel beam, the end of the channel beam projecting through the slot and the end of the
15 wooden beam being bolted to the said tongue.
6. In a car, the combination of an end sill having a transverse vertical web and a longitudinal vertical web in front thereof,
20 said transverse web having an opening therethrough, and a longitudinal center sill comprising a channel beam having the end
25 of its web projecting through said opening and laid against the said longitudinal vertical web of the end sill and riveted thereto. 25
7. In a car, an end sill comprising front and rear vertical plates and a horizontal connecting web, said plates and web being formed integrally, and the rear plate having an opening through which a center sill 30 member may project.
8. In a car, the combination of an end sill and a center sill member, the center sill member consisting of a channel beam embracing a wooden timber and projecting beyond the same, and the end sill having an opening in its rear face to receive the end of the channel beam while the end of the wooden timber abuts said rear face. 35
